UNITED STATES PATENT OFFICE.

FREDERICK J. HALL, OF WALLINGFORD, CONNECTICUT, ASSIGNOR OF ONE-HALF TO SILAS L. HALL, OF SAME PLACE.

SPOOL-HOLDER.

SPECIFICATION forming part of Letters Patent No. 363,330, dated May 17, 1887.

Application filed October 20, 1886. Serial No. 216,755. (No model.)

To all whom it may concern:

Be it known that I, FREDERICK J. HALL, a citizen of the United States, residing at Wallingford, Connecticut, have invented new and useful Improvements in Spool-Holders, of which the following is a specification.

This invention relates to certain new and useful improvements in spool-holders to be worn upon a button or portion of the clothing of seamstresses while sewing, the same consisting substantially in such features of construction and arrangement as will hereinafter be more particularly described and claimed.

In this class of inventions the primary object is to enable a spool of thread to be worn at a convenient place on the clothing of the seamstress while sewing, by which to save time when the thread is needed and avoid loss or misplacement of the spool, as frequently otherwise occurs.

The object of my invention is to produce a contrivance of this character by which may be had a ready attachment to and detachment from a button or portion of the clothing of the user by the simple act of closing together the parts of which it is constituted, and also to simplify and cheapen the cost of manufacture thereof, as will more fully appear herein-after.

Referring to the accompanying sheet of drawings, Figure 1 represents a front elevation of a spool-holder embodying my invention. Fig. 2 is an edge or side view thereof. Fig. 3 is a view of one portion to show more clearly the manner in which the parts are formed; and Fig. 4 is a view of a modification.

In carrying my invention into effect I take two pieces of wire, A A, and at a short distance from one end bend or coil them a single time, as at a, by which to form a loop or eye, b. I then bend the longer extremity thereof outward and downward, as at c d, and thence back or inward at a right angle, as at e, leaving a free end or portion for entering the opening through the spool, and the upper or shorter extremity is also bent at a right angle oppositely to e, as seen at f. After thus bending or forming the wires A A, I place the loop b of one over the like loop of

the other, with the bends f opposite to each other, and insert through the loops a securing pin or stud, g, which provides a bearing or fulcrum on which the wires are free to be operated in the attachment of the device to and its detachment from the button around the shank of which it is placed, and also bringing the lower extremities, e, opposite each other for entering the two ends of the spool. It will be seen that by this manner of forming the holder the upper extremities of the wires are made to cross each other, as seen at h, thus forming an opening, i, for the entrance and guidance of the thread from the spool. It will also be seen that in forming the coil a the upper bends, f, of the wires will be brought in different planes, thus permitting them to pass each other in closing around the shank of the button, and thereby insuring a perfect fastening without liability of tearing off the button.

If desired, the ends f may be pointed, and thus could they be made to enter a portion of or a fold in the garment and be secured. I prefer, however, that they shall not be pointed. Instead of forming the loop b of a coil in the wire, it may be formed by simply crimping the wire, as seen at a', Fig. 4, and then slightly turning the loop to one side in order to bring the ends f in different planes, as in the manner of Fig. 1.

The spool is inserted by drawing the two lower extremities apart and then bringing them together with the portions e entering the opposite ends of the spool. The upper extremities are placed around the button by simply pulling them apart and then drawing them together around the shank thereof.

It is evident that instead of forming my spool-holder of wire I may form the parts of flat metal, employing suitable dies for stamping them out.

Having thus described my invention, what I claim as new, and desire to secure by Letters Patent, is—

1. As an article of manufacture, a spool-holder consisting of two wires crossing each other and pivotally united by a stud, the same having their upper extremities bent opposite

to each other to embrace the shank of a button and their lower ends similarly bent to receive a spool, substantially as described.

2. As an article of manufacture, a spool-
holder consisting of two wires bent as at *c*, *d*,
e, and *f*, and formed with loops or coils *b*, to
bring their upper ends in different planes, and
a pivot or stud uniting the wires through the
loops and forming thereby the opening *i*, sub-
stantially as shown and described.

In testimony whereof I have hereunto set my
hand in the presence of two subscribing wit-
nesses.

FRED. J. HALL.
